UNITED STATES PATENT OFFICE

100,124

DESIGN FOR A BAR CABINET

David C. Rockola, Chicago, Ill.

Application September 3, 1935, Serial No. 58,414

Term of patent 3½ years

To all whom it may concern:

Be it known that I, David C. Rockola, a citizen of the Dominion of Canada and a resident of Chicago, in the county of Cook and State of Illinois, have invented a new, original, and ornamental Design for a Bar Cabinet, of which the following is a specification, reference being had to the accompanying drawing forming a part thereof, and in which:

The single figure is a perspective view of a bar cabinet showing my new design.

I claim:

The ornamental design for a bar cabinet, as shown.

DAVID C. ROCKOLA.
